SOUND WARNING DEVICE

Bernard Louis Joseph Fernand Le Roux,
Paris, FranceApplication August 8, 1945, Serial No. 609,627
In France July 1, 1944Section 1, Public Law 690, August 8, 1946
Patent expires July 1, 1964

5 Claims. (Cl. 161—23)

1

The object of the present invention is a sound warning device intended to give warning that a certain time period has elapsed since a time of origin, said warning device being designed in such a manner that it is capable of successively giving warning that several periods of time have elapsed. This device, which is adaptable to many purposes, is however more particularly intended to serve as a time indicator for the cooking of food and it thus constitutes a valuable help to housewives, restaurant cooks, etc.

This device is essentially constituted by a bell-ringing mechanism similar to that of an alarm clock, and is actuated by a clockwork mechanism adapted to operate for a limited period, for instance two hours. This bell-ringing mechanism is locked when it is not required to operate but is mounted on a movable mounting adapted to move along the axis of rotation of a needle or hand driven by the clockwork mechanism. This hand, which in its sliding movement is integral with the movable mounting comes into contact with movable push studs secured to the dial, at predetermined places, in such a manner that when the hand meets one of these push studs, it is urged outwardly, thereby actuating the movable mounting and the bell-ringing mechanism is unlocked. The bell is sounded, but the hand continues its travel, becomes released from the push stud and, under the action of a retracting spring, is brought back to its initial position in which the bell-ringing mechanism is again locked until the hand passes over the following push stud, in the event of the device being equipped to give warning of several operative periods.

The device in accordance with the invention furthermore comprises several detail features which will be apparent from the description hereinafter given with reference to the accompanying drawings which illustrate, by way of example, a form of embodiment of such a device as applied to giving warning of the time during which food is to be cooked. In said drawings:

Fig. 1 is a front view of the warning device.

Fig. 2 is a section through the line *a—b* of Fig. 1.

Fig. 3 is a front view of the control mechanism for the bell-ringing mechanism.

Fig. 4 is a front view of the locking mechanism of the bell-ringing mechanism.

Fig. 5 is a view of the apparatus dial, the hand being removed.

The apparatus is constituted by a casing 1, formed on the one hand, by an end plate 2 to which is secured a conventional clockwork mech-

2

anism 3 so wound up as to be able to operate for two hours and, on the other hand, by a front dial 4, graduated for example in minutes, from 0 to 120. This dial comprises a circular groove 5 having the same centre as the dial, the central portion of the dial being connected to the outer annular portion, which is outside the said groove 5 and carries the divisions in minutes, by a connecting ring 6. In said groove, there may be moved by hand push studs 7 comprising a convex head projecting forwardly of the dial and a screw-threaded rod on which is secured, behind the dial, a nut 8, so tightened that the push stud may remain on the dial in any position and that only a slight effort is required to move it.

The end of the casing 2 carries, through the medium of stays 9, one of the assembling plates 10 for the bell ringing mechanism which is connected by stays 11 to the second plate 12. To the latter is secured the bell proper 13 on which may strike a hammer 14 pivoting about a pivot 15. The end of the hammer pivot (Fig. 3) carries a control pin 16 on which act the teeth of a pinion 17, the hammer being, on the other hand subjected to the action of a retracting spring 18. The pinion 17 is centered on the spindle 19 of the clockwork mechanism 3.

This spindle, which passes through the dial 4 by means of a guiding member 20, carries a pin 21 serving to rotate a sleeve 22 surrounding the spindle 19 and which is adapted to slide thereon by means of a groove 23 which is engaged by said pin 21. This sleeve actuates, in its sliding movement, a shifting pinion 24 which otherwise freely rotates thereon and which is integral, on the one hand, with a bell pinion 17 and, on the other hand with a square-notched pinion 25 for stopping the bell, stoppage being effected by the engagement of a pin 26, carried by the plate 10, in one of the notches (Figs. 2 and 4). These three pinions are comprised between two stop rings 27—27.

On the spindle 19 of the clockwork mechanism is keyed a pinion 28 which meshes with the pinion 29 for winding up the bell spring. This pinion is freely mounted on the spindle 30 of the bell spring 31 and is clamped between two friction plates 32, the friction effect of which may be adjusted by means of the screw 33, integral with the spindle 30. The end of the spring 31 is secured to the stop pin 34 (Figs. 2, 3 and 4). On the spindle 30 is keyed the ratchet wheel 35 the retaining pawl of which is shown at 36. This wheel is integral with the pinion 37, meshing with the shifting pinion 24.

The unwinding of the bell spring 31 is adjusted by a braking mechanism constituted by a button 38 on the spindle 39 ending in an enlarged portion 40 acting on the cheek of the pinion 37 and subjected to the action of a spring 41.

On the end of the tubular spindle 22 projecting in front of the dial is keyed a winding knob 42, which is integral with the hand 43. A spring 44 bearing, on the one hand, on the guiding member 20 and on the other hand on a stop ring 45 secured to the sleeve 22, constantly urges the latter, together with the movable mounting integral therewith, towards the inside of the apparatus.

The dial has the appearance shown in Fig. 5. It carries on concentric circles indications concerning the time required for cooking various foods (meat, fowls and game, fish, vegetables, pastry, etc.) in function of the amounts of these foods to be prepared. If desired, this dial may also contain indications concerning the temperature to be reached in order to ensure satisfactory cooking of each of these foods.

The apparatus may be hung on a partition, a wall for example, by means of lugs 46 integral with the casing and provided with holes 47 for the passage of screws or nails.

The operation of this device is as follows:

The apparatus is wound up by acting on the knob 42 which is rotated in an anti-clockwise direction. The purpose of this operation is firstly to wind up the clockwork motor 3 and, on the other hand, through the medium of the pinions 28 and 29, the friction cheeks 32, the spindle 38, the ratchet wheel 35-36, to wind up the bell spring 31. When the winding up operation is completed, the hand 43 is situated in front of zero on the minutes scale.

The push studs 1 are brought opposite the graduations corresponding to the articles of food to be cooked and the apparatus is ready to operate. Under the action of the spring 44, the unit comprising the hand 43, sleeve 22, shifting pinion 24, is urged towards the right of Fig. 2 and the pin 26 enters one of the notches of the pinion 25. The bell mechanism is therefore locked and cannot operate. However, when the hand 43, actuated by the clockwork mechanism, passes in front of a push stud 7, it is pushed away from the dial and it draws along with it the movable mounting by an amount such that the locking pinion 25 is released from the pin 26. The shifting pinion 24, being actuated by the pinion 37, may then rotate, and in its turn drive the pinion 17 which, by acting on the pin 16 of the hammer 14, causes the bell to ring.

As soon as the hand 43, during its travel, has gone beyond the push stud 7, the spring 44 which has been compressed, pushes back the movable parts towards the right of Figure 2 and the bell ringing mechanism is once more locked.

I claim:

1. Time warning device comprising, in combination, an actuating clockwork mechanism, a bell-ringing mechanism normally in a locked position, a hand rotatable in front of a graduated dial, push studs movably mounted in a circular groove on said dial and provided with a head projecting in front of said dial sufficiently to push the said hand outwardly as it rotates over one of said push studs thereby drawing away with it part

of the bell-ringing mechanism and thus unlocking it, spring means for returning the said part of the bell-ringing mechanism into its locked position, a knob integral with the said hand for winding up the whole mechanism whereby the said hand is brought in front of the zero of the graduated scale at the end of the winding operation.

2. Time warning device comprising, in combination, an actuating clockwork mechanism, a bell-ringing mechanism normally in a locked position, a hand rotatable in front of a graduated dial, push studs movably mounted in a circular groove on said dial and provided with a head projecting in front of said dial sufficiently to push the said hand outwardly as it rotates over one of said push studs thereby drawing away with it part of the bell-ringing mechanism and thus unlocking it, spring means for returning the said part of the bell-ringing mechanism into its locked position, a knob integral with the said hand for winding up the clockwork mechanism and an adjustable friction device transmitting the winding movement of the clockwork mechanism to the bell-ringing mechanism whereby the latter is wound up concomitantly with the clockwork mechanism.

3. Time warning device comprising in combination, a clockwork mechanism, a bell-ringing mechanism normally in a locked position, a hand mounted at the end of a hollow tube actuated by the central spindle of the clockwork mechanism and adapted to slide therealong, said hand being rotatable in front of a graduated dial, push studs slidably mounted in a circular groove on said dial and provided with a head projecting in front of said dial sufficiently to push said hand outwardly as it passes over one of said push studs, a shifting pinion carried by the said tube and adapted to unlock the bell-ringing mechanism when said tube slides on said central spindle as a result of the said hand being pushed by one of said push studs, spring means for returning the said tube and the said shifting pinion into their initial position in which the bell-ringing mechanism is locked, and means for winding up the whole mechanism.

4. Time warning device according to claim 3 in which the said shifting pinion is integral with a square notched pinion with which engages a pin carried by a fixed portion of the mechanism when the bell ringing mechanism is in the locked position.

5. Time warning device according to claim 3 in which a braking device is provided for regulating the speed of unwinding of the spring of the bell-ringing mechanism.
